UNITED STATES PATENT OFFICE.

ALLEN EARLY, OF AMARILLO, TEXAS.

ROPE GUIDE AND PROTECTOR.

1,147,792.

Specification of Letters Patent.

Patented July 27, 1915.

Application filed September 14, 1914. Serial No. 861,712.

To all whom it may concern:

Be it known that I, ALLEN EARLY, a citizen of the United States, residing at Amarillo, in the county of Potter and State of Texas, have invented certain new and useful Improvements in Rope Guides and Protectors, of which the following is a specification.

The present invention relates to improvements in rope guides and protectors.

An object of the invention resides in the provision of a rope guide and protector especially adapted for use in connection with apparatus for unloading grain from cars, to prevent the rope from wearing during its passage around the door jamb of the car, and also to prevent friction during such passage of the rope, thereby making it possible to use the shovel with the application of but comparatively little power.

Another object of the invention is the provision of a rope guide and protector so constructed that the same can be removably applied to the door jamb of a car and which can be removed when not in use.

A further object of the invention is the provision of a rope guide and protector which includes a rectangular frame having spaced horizontal flanges for supporting the rollers and oppositely extending side flanges for receiving fastening elements by which the frame can be secured to the door jamb of a car.

A still further object of the invention is the provision of a rope guide and protector which will be comparatively simple and inexpensive, reliable and efficient in use, and readily applied to the door jamb of a car.

With the above and other objects in view the present invention resides in the novel features of construction, formations, combinations and arrangements of parts to be hereinafter more fully described, claimed and illustrated in the accompanying drawing, it being understood that various minor changes in the specific details of construction may be resorted to within the scope of the appended claims, without departing from the spirit or sacrificing any of the advantages of the invention.

In the accompanying drawing forming a part of this application: Figure 1 is a fragmentary sectional view of a grain car, showing my invention applied thereto; Fig. 2 is an enlarged detail perspective view of the

rope protector and guide removed showing a portion of the door jamb in dotted lines.

Referring to the accompanying drawing by similar characters of reference throughout the several views, the numeral 5 designates a portion of a grain car having a door opening 6 formed in one side thereof.

The usual unloading apparatus is indicated by the numeral 7 and consists of a shovel 8 and operating rope 9 which is drawn by any suitable source of power (not shown in the drawing), but positioned outside of the car.

My improved rope guide and protector 10 is detachably secured to one side of the door jamb 11 and consists preferably of a rectangular metallic frame 12 having the opposite vertical side members 13 and upper and lower horizontal connecting members 14.

Parallel flanges 15 are formed upon the outer edges of the members 14 and are provided with spaced bearings 16 in which are journaled the trunnions 17 of the spaced antifriction guide rollers 18, the sides of which extend preferably beyond the outer edges of the vertical side bars 12 for preventing any contact of the rope 9 with said bars 12 which would cause the latter to become worn and break.

Side flanges 19 are formed upon the opposite outer edges of the vertical members 12 and engage the opposite edges of jamb 11, serving to retain the frame 10 in engagement with the inner side of said jamb 11, as clearly shown in Figs. 1 and 2.

The flanges 19 are formed with threaded openings, 20, for receiving the thumb screws 21 or other suitable fastening devices which can be forced into engagement with the opposite sides of the jamb, thereby retaining the frame 10 in its proper position against any undesired displacement.

Obviously when the rope 9 is placed in engagement with the rollers 18, the latter will act as a guide for the rope and also protect the same against any wear in its constant passage over the door jamb, during the unloading of the grain.

From the foregoing description taken in connection with the accompanying drawing it will be manifest that rope guide and protector is provided which will fulfil all of the necessary requirements of such a device.

Having thus fully described the invention what I claim as new and desire to protect by Letters Patent is:

1. In a rope guide and protector, a frame comprising opposite side members and upper and lower connecting members, all of said members being spaced to provide the frame with a central opening, spaced upper and lower flanges on the frame, securing flanges on the frame, and rollers journaled in said upper and lower flanges and arranged along opposite sides of the opening in the frame.
2. In a rope guide and protector, a frame comprising opposite side members and upper and lower connecting members, spaced flanges formed upon the said side members, fastening devices passing through said side flanges, spaced flanges formed upon the connecting members, and rollers journaled in said last mentioned flanges.

3. In a rope guide and protector, the combination of a rectangular frame including opposite side members and upper and lower connecting members, flanges formed upon the side members, fastening devices passing through said flanges for removably connecting the frame to the door jamb of a grain car or the like, horizontal flanges formed upon the connecting members, said flanges having bearings provided therein adjacent the ends thereof, and rollers journaled in the bearings and extending beyond the outer edges of the side members of the frame.

In testimony whereof I affix my signature 35 in presence of two witnesses.

ALLEN EARLY.
